UNITED STATES PATENT OFFICE.

JOHN ERICSSON, OF NEW YORK, N. Y., ASSIGNOR OF ONE-HALF TO CORNELIUS H. DELAMATER AND GEORGE H. ROBINSON, BOTH OF SAME PLACE.

FIRING-PIN FOR PROJECTILE-TORPEDOES.

SPECIFICATION forming part of Letters Patent No. 245,803, dated August 16, 1881.

Application filed June 18, 1881. (No model.)

To all whom it may concern:

Be it known that I, JOHN ERICSSON, of the city, county, and State of New York, have invented certain new and useful Improvements in Percussion Apparatus for Firing the Charges of Explosive Projectiles, of which the following is a specification, reference being had to the accompanying drawings.

This invention relates to that class of percussion apparatus for firing the explosive charges of submarine torpedoes and other explosive projectiles in which a firing-pin protruding from a socket inserted into the projectile has applied to it a spring, which, until the projectile strikes the vessel or body attacked, holds the said pin out of contact with the primers or fulminate employed to ignite the charge.

The invention consists in certain novel features in the construction of such percussion apparatus, whereby its accidental operation is effectually prevented, although greater certainty of firing the charge on the striking of the projectile is insured.

Figure 1 is a central longitudinal section of my improved percussion apparatus and of a part of the head of a torpedo to which it is applied. Fig. 2 is a front view of the plug which closes the rear end of the socket of the said apparatus, and which receives the primers or fulminate-containing devices by which the charge is ignited.

S is a socket which contains all the parts of the percussion apparatus, and which is screwed at *n* into the head *a* of the projectile, and which enters the chamber *B*, which contains the explosive charge.

P is the firing pin, centrally placed within the said socket *S*, protruding from the front thereof.

Q is a very strong coiled spring arranged around the said firing-pin within the said socket.

R is a plug screwed into the rear of the said socket, and having in it two or more holes serving as receptacles for as many fulminate primers or cartridges *m m*. This plug is secured against turning in the socket by a screw, *v*, passing through the socket and screwing into the said plug, and the primer-receptacles and the primers or cartridges contained therein are thereby secured in certain positions.

The firing-pin is straight and provided with a collar or shoulder, *P'*, at some distance from its rear end. Its front end is made with a chisel-point or otherwise with a sharp edge, to prevent it from glancing off from a vessel which it strikes. Its rear end is furnished with two or more teats, *o o*, or points intended to strike the fulminate cartridges or primers *m m*. The socket *S* is bored centrally and has in its front end a stuffing-box, *T*, through which the firing-pin works water-tight, and by which water is excluded from the socket. The bore is enlarged some distance behind the stuffing-box sufficiently to receive the collar *P'* and the spring *Q*, the said spring and the pin being inserted into the socket from the rear before the plug *R* is put in. In front of this plug there is inserted into the socket a collar, *R'*, which is held by the plug against a shoulder, *p*, formed by a further enlargement of the bore behind the portion which receives the spring. This collar serves as a guide for the rear end of the firing-pin and as an abutment for the spring which is powerfully compressed between the said collar *R'* and the collar *P'* on the firing-pin, and holds the latter so securely against a shoulder, *p*, in the socket that no possible accidental concussion on the front end of the firing-pin could drive back the said pin in the socket.

The teats or points *o o* on the rear end of the firing-pin and the fulminate cartridges or primers *m m* correspond in number and position, and in order to preserve the proper positions of the said teats or points relatively to the said cartridges or primers, and so insure each of the said points or teats striking properly one of the said cartridges or primers when the firing-pin is driven back into the socket *S*, there is a longitudinal slot, *r*, in the socket, in which fits a pin, *t*, which is screwed into a tapped hole in collar *P'* and projects laterally from the firing-pin. When the collar *P'* of the firing-pin is held against the shoulder *p* the points or teats *o o* are some distance from the cartridges or primers. These cartridges or primers may in all respects resemble the metallic cartridges commonly used for small arms, and be either what are known as "center-fire" or "rim-fire." The firing-pin being kept from

turning by the pin *t*, and the plug *R* being kept from turning by the screw *v*, the striking of all the cartridges or primers is insured, and the firing of the explosive charge in the projectile cannot fail from the missing fire of the cartridges or primers *m*, unless the whole number should miss, and it is hardly within the range of possibility that all should miss, when the front end of the firing-pin strikes a vessel or other body attacked with the impact due to the momentum of the projectile when discharged from a gun.

What I claim as my invention is—

1. The combination, in a percussion-firing apparatus for explosive projectiles, of a socket having in its rear end fixed receptacles for two or more fulminate-primers, and a firing-pin having a number of teats or points corresponding

with the said receptacles, and having a lateral projection working in a slot in said socket for the purpose of keeping each point or teat of the firing-pin opposite one of the primer-receptacles, substantially as herein described.

2. The combination of the socket *S*, provided with a shoulder, *q*, the firing-pin *P*, provided with a collar, *P'*, the spring *Q*, the collar *R'*, serving as a guide for the firing-pin and an abutment for the spring, and the plug *R*, serving to hold the fulminate-primers and to secure the collar *R'*, substantially as herein described.

J. ERICSSON.
